UNITED STATES PATENT OFFICE

2,079,955

BEACON SUNRAY LIGHT

Mary Ellen Woodward, Lexington, Ky.

Application May 7, 1935, Serial No. 20,233

1 Claim. (Cl. 240—25)

This invention relates broadly to the class of illumination and has as its object the provision of a simple, inexpensive and efficient electric lamp especially adapted for use in public parks; 5 and further to provide such a lamp which besides being useful will also be attractive and ornamental in appearance.

The invention together with its objects and advantages will be best understood from a study 10 of the following description taken in connection with the accompanying drawing wherein:

Figure 1 is an elevational view of the lamp.

Figure 2 is an enlarged sectional view taken substantially on the line 2—2 of Figure 1.

15 Figure 3 is an edge elevational view of an annular frame forming part of the invention.

Referring to the drawing by reference numerals it will be seen that the lamp comprises a post 5 of any suitable shape, design and length 20 rising from a suitable and preferably ornate base 6. The post 5 is bored or hollow to accommodate an electrical conductor leading to a suitable socket 7 mounted at the top of the post 5 to accommodate an electric light bulb 8.

25 The socket 7 is arranged within the confines of a vertically disposed continuous circular frame 9 provided with a vertical central series of circumferentially spaced minute apertures 10' through which the rays from the bulb 8 30 pass to provide substantially a halo of light about the globe.

The aforementioned globe in the present instance consists of the frame 9 and concavo convex transparent disks 10 the convex surfaces 35 of which are disposed outwardly. At the edges thereof the disks 10 are provided with inwardly directed circular flanges 11 of a diameter to fit snugly within the frame 9 and through the

medium of which and set screws 12 the disks 10 are removably held in place.

It will be apparent that the light rays from the globe 8 will shine not only through the disks 10 but also in tiny pin points of light through the 5 apertures 10' affording not only the desired illumination but also giving an attractive and enhancing appearance to the lamp.

As will be appreciated from the foregoing, my novel lamp while well adapted to serve the purpose ascribed to it is extremely simple and inexpensive in construction and entails the employment of but a minimum number of parts, and is at the same time strong and durable.

Having thus described the invention, what is 15 claimed as new is:

The herein described improved lamp comprising essentially a post with a vertical bore therethrough, a circular frame or band superimposed on and corresponding in width with the 20 diameter of the upper end of the post and arranged throughout in the same vertical plane as the upper end of the post and having a vertical central series of minute spaced apertures for the radial emanation of light rays, a lamp socket 25 bearing directly on the lower portion of said circular band or frame and holding the same to the upper end of the post, an incandescent electric lamp bulb carried in said socket, diaphanous disks arranged at opposite sides of said circular 30 band or frame and having inwardly directed flanges fitting snugly within the edge portions of the circular band or frame, and screws threaded in apertures of the circular band or frame and disposed in indentures in the flanges of the diaphanous disks for positively though detachably securing the disks in the circular band or frame. 35

MARY ELLEN WOODWARD.
